UNITED STATES PATENT OFFICE.

CHARLES P. WINEMAN, OF DETROIT, MICHIGAN, ASSIGNOR TO DETROIT TWIST DRILL COMPANY, OF DETROIT, MICHIGAN, A CORPORATION OF MICHIGAN.

METHOD OF FORMING DRILLS.

Application filed June 13, 1921. Serial No. 477,027.

To all whom it may concern:

Be it known that I, CHARLES P. WINEMAN, a citizen of the United States of America, residing at Detroit, in the county of Wayne and State of Michigan, have invented certain new and useful Improvements in Methods of Forming Drills, of which the following is a specification, reference being had therein to the accompanying drawings.

- 10 The invention relates to the manufacture of drills and refers particularly to those made of high speed steel. It is an object of the invention to form a drill with as little structural distortion of the blank 55
 15 which the drill is formed as possible and also form a drill in such a manner as to save material by utilizing all the stock in the blank. Another object is the forming of recesses in 60
 20 the blank to assist in holding the same while a portion thereof is being upset to form the drill shank. A further object is the rounding of the corners of the drill blank to facilitate the passage of the same through the 65
 25 groove forming rolls. With these objects in view, the invention resides in the novel features more fully hereinafter set forth.

In the drawings:

Figure 1 is a perspective view of one of the die blocks for forming the drill and 30 showing the blank in its first position;

Figure 2 is a cross section through the original drill blank;

Figure 3 is a cross section through the drill blank on the line 3—3 of Figure 1;

35 Figures 4 and 5 are side elevations of the die block showing the drill blank in its second position respectively before and after being operated upon;

Figures 6, 7 and 8 are cross sections 40 through the drill blank respectively on lines 6—6, 7—7 and 8—8 of Figure 5;

Figure 9 is a side elevation of the die block showing the drill blank in its third position;

45 Figure 10 is a cross section through the drill blank on the line 10—10 of Figure 9;

Figure 11 is a side elevation of a drill blank after it has passed through the groove forming rolls.

50 1 is one of a pair of identical die blocks having in its inner side the open ended recess 2 with the shoulder 3 at its inner end, and the parallel grooves 4 and 5 with open ends.

The drill blank 6 is a bar formed of high speed steel of sufficient length to form several drills and has originally a rectangular cross section as shown particularly in Figure 2. The thickness of this blank is substantially equal to the thickness of the segment of the fluted portion of the drill while the width of the blank is substantially equal to the width of the fluted portion. This blank is first inserted into the recess 2 with its end abutting against the shoulder 3 and its shorter sides parallel to the inner face of the die block so that upon operation of the die blocks, the end 7 of the blank is upset so that it will have a cross section as shown in Figure 3 in which the thickness is increased and the transverse dimensions will 70 be substantially equalized.

As shown in Figures 4 and 5, the second position of the drill blank is within the groove 4 with the upset end 7 abutting a suitable limit gauge 8. This groove has the rounded portion 9 at one end adapted to receive the upset end 7, the substantially rectangular portion 10 for receiving the remainder of the drill blank with its longer sides parallel to the inner face of the die block, and also the lug or projection 11 at the inner end of the rounded portion 9, so that upon the moving of the two die blocks together, the projections 11 will form recesses 12 in the opposite sides of the drill blank. After these die blocks have been brought together the upset end 7 of the drill blank is further upset by suitable means which in the present instance is the member forming the limit gauge 8 so that the completed upset end 95 of the drill blank as shown in Figure 6 is circular in cross section. Due to the fact that the steel of which the drill is formed is high speed steel, it is particularly desirable to form the recesses in the drill blank to hold the same while it is being upset to form the shank. It is obvious in this connection that a separate limit gauge and heading tool can be used instead of having the one member to effect both functions.

Figure 9 shows the drill blank in its third position in the die block in which position the shorter sides of the portion 13 of the drill blank which has not been operated upon, are positioned parallel to the inner face of the die block, so that when the two 105

die blocks are brought together, the corners of this portion will be rounded so that the same will have a cross section as shown in Figure 10. After the corners have been rounded, the bar of stock is severed by suitable means to predetermined length.

The drill blank is next passed through the groove forming rolls, the grooves formed in the drill blank registering with the recesses 12 and being sufficiently deep so that these recesses do not appear in the drill blank after it has passed through the drill forming rolls as shown in Figure 11.

What I claim as my invention is:

- 18 1. In the method of making a drill, the forming of a shoulder on a polygonal blank to hold the same from longitudinal movement, and the upsetting of a portion of the blank to one side of the shoulder to form the drill shank while the shoulder is holding the blank from longitudinal movement.
- 20 2. In the method of making a drill, the forming of a recess in the drill blank to assist in holding the same from longitudinal movement, the upsetting of a portion of the drill blank to form the shank for the drill, and the form rolling of another portion of the blank to form the fluted portion of the drill.
- 25 3. In the method of making a drill, the forming of recesses in opposite sides of a polygonal blank to assist in holding the blank from longitudinal movement, the upsetting of an end portion of the blank to one side of the recesses to form a shank for the drill, and the forming of grooves in another

portion of the blank and registering with the recesses to form the fluted portion of the drill.

4. In the method of making a drill, the forming of recesses in opposite sides of a polygonal blank to assist in holding the same from longitudinal movement, the upsetting of an end portion of the drill to one side of the recesses to form a shank for the drill, the rounding of the corners of another portion of the blank and the form rolling of said last-mentioned portion of the blank to form grooves in the blank registering with the recesses. 50

5. In the method of making a drill, the upsetting of an end portion of a rectangular bar to increase the thickness thereof, the forming of recesses in the wider sides of the rectangular bar adjacent to the upset end portion, the upsetting of the upset end portion to form a rounded shank for the drill, the rounding of the corners of another portion of the rectangular bar, the form rolling of said last-mentioned portion of the rectangular bar to form grooves in opposite sides thereof registering with the recesses, and the severing of the rectangular bar to predetermined length. 55

6. In the method of making a drill, the forming of a recess in the drill blank and the forming of a groove in a portion of the blank and registering with the recess to form the fluted portion of the drill. 60

In testimony whereof I affix my signature. 70

CHARLES P. WINEMAN.
